UNITED STATES PATENT OFFICE.

JAMES W. CAMERON, OF NEW YORK, N. Y.

HAND-WHEEL GUARD.

SPECIFICATION forming part of Letters Patent No. 520,410, dated May 29, 1894.

Application filed June 29, 1893. Serial No. 478,107. (No model.)

To all whom it may concern:

Be it known that I, JAMES W. CAMERON, a citizen of the United States, and a resident of New York, in the county of New York and State of New York, have invented certain new and useful Improvements in Hand-Wheel Guards, of which the following is a specification.

My invention relates to a new manufacture, 10 namely, a guard for hand wheels, as herein-after more particularly described and illustrated in the accompanying drawings, in which—

Figure 1 represents an inverted plan view 15 embodying my invention. Fig. 2 represents a sectional view thereof. Fig. 3 represents a top or plan view embodying my invention. Fig. 4 is a sectional view showing a way of securing the guard to the valve or hand wheel 20 by means of wires. Fig. 5 represents a plan view of another way of fastening the cover to the wheel. Fig. 6 represents an inverted plan view of the same. Fig. 7 represents a view of the cover detached from the wheel, 25 and provided with wires for attachment thereto. Fig. 8 represents a view of one of the blocks for fastening the cover to the wheel, detached.

Similar letters of reference indicate corresponding parts.

The letter A designates an ordinary valve wheel constructed of metal in the usual way.

The letter B designates the body of the detachable hand wheel guard which may be 30 composed of wood, asbestos, plastic composition or any other suitable material of a non-heat conducting nature. It is made circular and has a hollow portion C forming a cover to conform to the general contour of the top 35 of the hand wheel A, so that when the guard B is placed on the wheel A it fits snugly thereon, and moreover, completely covers the

top and circumference of the hand wheel and guards the hand from injury.

In order to secure the guard to the wheel 45 I insert wires D at proper places in the body in openings beveled from the outside inward so that the wires can be drawn around the arms E of the steam wheel A and fastened in any suitable manner, as shown in Figs. 1, 3, 50 4 and 4. The wires D may also be sunk below the surface of the body of the guard so they will not touch the hand as shown in Fig. 2. Or little plates or blocks G may be fitted in the spaces between the spokes and fastened 55 from the outside with counter sunk screws H which will also be let in the wood a little as shown in Figs. 6 and 7; or the guard may be sprung over the periphery of the wheel and thereby be held in position. 60

The advantage gained by the use of the guard B is that it requires the least preparation for its adaptation to its desired purpose on the wheels, while it affords a simple and effective shield from the heat, and at the same 65 time its manufacture is attended with the least possible cost.

What I claim as new, and desire to secure by Letters Patent, is—

The herein described circular cap-shaped 70 hand wheel guard, of a non heat conducting nature for use on steam hand wheels having a hollow portion C to conform to the general contour of the hand wheel completely covering the top and circumference thereof, and provided 75 with counter-sunk wires to secure the guard to the wheel in such a manner as to prevent injury to the hand, substantially as shown and described.

JAMES W. CAMERON.
